Primary Examiner — Joseph Kukella*Assistant Examiner* — Mark T. Philipp(74) *Attorney, Agent, or Firm* — Hanley, Flight & Zimmerman, LLC(57) **CLAIM**

The ornamental design for a "fluid pump," as shown and described in FIGS. 1-5.

DESCRIPTION

FIG. 1 is a front, right perspective view of a fluid pump.

FIG. 2 is a front view of the fluid pump of FIG. 1.

FIG. 3 is a rear view of the fluid pump of FIG. 1.

FIG. 4 is a right view of the fluid pump of FIG. 1.

FIG. 5 is a left view of the fluid pump of FIG. 1.

FIG. 6 is a top view of the fluid pump of FIG. 1; and,

FIG. 7 is a bottom view of the fluid pump of FIG. 1.

The broken lines depict features of the fluid pump that form no part of the claim.
